United States Patent Office

Des. 232,370
Patented Aug. 13, 1974

232,370

SIT-UP EXERCISER

John Hasekian, 108 Putnam, Watertown, Mass. 02172

Filed Oct. 16, 1972, Ser. No. 297,781

Term of patent 14 years

Int. Cl. D21—02

U.S. Cl. D34—5 K

FIG. 1 is a top perspective view of a sit-up exerciser showing my new design;

FIG. 2 is a side elevational view thereof;

FIG. 3 is a bottom and opposite side perspective view thereof.

I claim:

The ornamental design for a sit-up exerciser, as shown.
